UNITED STATES PATENT OFFICE.

IRVING COWLES, OF CHICAGO, ILLINOIS, ASSIGNOR TO UNION BANK OF CHICAGO, OF CHICAGO, ILLINOIS, A CORPORATION OF ILLINOIS.

AUTOMATIC AIR-SUPPLY VALVE FOR ICE PANS.

Application filed August 12, 1925. Serial No. 49,865.

This invention relates to improvements in air supply valves for artificial ice making plants to feed air under pressure into the water-freezing pans for the purpose of maintaining the contained water in circulation during freezing thereof to thereby prevent the formation of the core or pocket, due to concentration of the hard salts, in the top of the cake of ice and also to prevent formation of so-called white ice, the main object of the invention being to provide an air feed valve which will insure constant supply of air up to the time that the water is solidly frozen throughout.

In artificial ice plants, air under pressure is supplied to each of the water pans through a metal tube depending into the same to a point contiguous to the bottom thereof, said metal tubes being detachably connected, by means of flexible rubber tubes, with the air supply pipes disposed above the pans. The air supply to each pan is now generally controlled by a pet-cock and great waste of compressed air thus results or, where fine adjustments are effected to avoid such waste, it is not infrequent that too little air is fed to prevent clogging of the discharge end of the metal tube by formation of ice therein. Constant watch and inspection is necessary to prevent the interruption and proper control of the air-supply to the numerous pans of every plant and even with these precautions, a fairly large percentage of white ice is produced and great waste of compressed air occasioned.

The objects of my present invention are:

First. To provide an air supply valve for each pan which will initially regulate and control the flow of air into each pan to maintain uniformity and prevent waste by feeding just enough air to maintain the required water-circulation.

Second. To provide an air supply valve which, upon choking of the tube by formation of ice in the discharge end thereof, will automatically and suddenly occasion the supply to the tube of a large volume of air under the pressure maintained in the air supply system, to thereby effect ejection of the ice plug formed in the discharge end of the tube and thereupon return to initial position to supply the continuous flow of the smaller volume of air.

Third. To provide a valve of the character aforesaid which may be easily adjusted

to supply the minimum air current necessitated by water conditions and which, furthermore, may be easily and quickly adjusted to supply a larger volume of air during any period desired by eliminating the automatic operation defined in the preceding paragraph or to accommodate the valve to a low-pressure supply system.

Fourth. To provide a valve of the character aforesaid, which will be self-cleaning.

Fifth. To provide a valve possessing the several advantages aforesaid, the several component parts of which may be easily and cheaply produced by automatic screw-machines or the like, supplemented by drill-press work, and which is small and compact.

The preferred embodiment of the invention is shown in the accompanying drawings, in which:

Fig. 1 is a central longitudinal section of a valve constructed in accordance with the invention.

Fig. 2 is a view similar to Fig. 1 showing a member of the valve in position to pass a larger volume of air and rendering the same practically non-automatic.

Fig. 3 is a detail perspective view of a piston valve constituting an element of the structure.

Figs. 4 and 5 are perspective sectional views of two parts of the valve housing.

Figs. 6 and 7 are views similar to Figs. 1 and 2, respectively, of a modified form of construction of an air supply valve which is non-automatic.

Fig. 8 is a transverse section on the line 8—8 of Fig. 6.

Fig. 9 is a detail perspective section of a valve element of the structure of Figs. 6 and 7.

Fig. 10 is a perspective section of an adjusting element employed.

Fig. 11 is a transverse section on the line 11—11 of Fig. 6.

Fig. 12 is a central longitudinal section of still another and very simple embodiment of the invention.

The valve comprises the housing element 1, preferably of external polygonal form, such as hexagon, which is provided at one end with an externally threaded, hollow axial stem 2 which is adapted to enter the threaded openings in a compressed-air supply pipe, not shown. The other end of said housing element 1 is open and internally

threaded to receive the externally threaded middle portion of a housing and valve-carrying element 3. The latter terminates at its upper end in an externally threaded annular flange 4 bordering a central cylindrical bore 5 which extends into but not through the body or middle portion 3, the flange 4 being of considerably smaller diameter than said middle portion. The latter is provided at its lower end with an externally smooth and internally threaded cylindrical flange 6, both said flanges being concentric with said middle or body portion 3.

15   Mounted within the bore 5 is a helical compression spring 7 which serves to normally maintain the piston 8 equipped with the cup-washer 9, at the outer or upper limit of its movement. A needle valve 10 is loosely 20 associated with said piston for reciprocation thereby, the same having ball and socket joint connection with the piston. Said needle valve 10 comprises a middle, cylindrical portion presenting a tapered surface 11 at 25 its upper end and terminating in a small, cylindrical projection 12 which extends through the air intake opening of the adjustable element 13 having threaded engagement with the cap 14 which is mounted on the 30 flange 4 and presents an internal annular shoulder 15 seating on the upper end of said flange 4 and projecting inwardly of the latter and into the path of the piston 8. The cup-washer 9 of the latter is surmounted by 35 the metal washer 9^a which engages said shoulder 15 when the piston is at the upper limit of its movement.

Surrounding the cap 14 is an annular space or air chamber 16 which communicates with the interior of the cap 14 through 40 the lateral opening 32 and with the bore of the flange 6 through the opening or passage 18. At the inner end of the bore of the stem 2 is the valve seat 19 on which the 45 conical upper end of the cap 14 is adapted to seat, to thereby compel all air entering the said bore to pass through the cap 14 and chamber 16.

The bore 5 communicates at its inner end 50 with atmosphere through the openings 20 and 21.

Connection between the bore of flange 6 and the lower end of an ice pan is effected 55 through the central bore 22 of the nozzle 23 to which the flexible hose 24 is adapted to be attached in any suitable manner, said hose being also attached to the metal tube 25, depending into the ice pan. Said nozzle constitutes the lower terminal element of the 60 member 26 provided with the externally threaded nipple 27 engaging in the flange 6. Said member 26 is provided with the annular hollow flange 28 on the bottom of which the helical compression spring 29 seats, said spring 29 bearing upon a metal

washer 30 which, in turn, bears upon the leather or similar flexible cup-washer 31 70 slidable upon the flange 6 and bearing upon the lower end of the housing element 1 to thereby seal the chamber 16 against escape of air through the threads associating the elements 1 and 3.

The member 13 includes the cylindrical flange bordering the central air intake opening therein, said cylindrical portion projecting through and snugly fitting the central opening in the upper end of the cap 14. Below said cylindrical portion, the member 13 presents a conical surface opposing the similar surface 11 of the valve 10 and spaced 80 from the latter a distance sufficient to readily permit passage of all air entering the central opening of said member around the projection 12. The last mentioned space determines the maximum air feed to the 85 pans when the element 13 is at the upper limit of its movement relatively to the cap 14 and the conical upper end of the latter is seated. By adjusting the position of said member 13 relatively to the cap 14 in the 90 direction of the piston 8, the space between the conical surface 11 of the valve 10 and the opposed similar surface of the element 13, may be contracted to limit the volume of air to less than the capacity of said central 95 air-intake opening, as will be obvious. The member 13 is provided with diametrically opposed recesses 17 in its inner end for engagement with a screw-driver for its adjustment, the latter being usually permanent. 100

The operation of the above described construction is as follows:—

Assuming that the air pressure maintained in the air supply pipe with which the stem 2 connects, is fifteen pounds per square inch, 105 then the spring 7 must be of such strength as to maintain the needle valve at the upper limit of its movement against the action of said air pressure, it being preferable that the said valve 10 be not seated to seal the opening in the member 13 though this might be done. The spring 7 may be adjusted to be normally slightly compressed by the air pressure on the needle valve 10 while maintaining the latter in such position as to limit 110 the normal flow of air to the desired minimum. The loose association of said needle valve with the piston 8 permits vibration of the same by the flowing air to thereby maintain the air intake opening free of corrosion and of obstruction other than is afforded by said projection 12 of the valve 10. 115

As the openings 18 and 32 are of larger diameter or area than the partially obstructed air intake opening, the air pressure developed within the cap 14 and chamber 16 120 can not possibly greatly exceed the hydrostatic head afforded by the water in the ice pan into which the tube 25 depends. Consequently, the piston 8 can be actuated 125 130

against the spring 7 only to the extent above indicated.

If an ice-plug should form in the discharge end of the tube 25, as not infrequently happens, and the flow of air be thus badly impeded or wholly interrupted, then, obviously, the pressure within the chamber 16 and cap 14 will instantly increase to the point (not above fifteen pounds) at which the flow of 10 air from the stem 2 continues. Such an ice-plug is rarely initially of more than film-like thickness but increases rapidly unless promptly broken. The very rapid accumulation of pressure in the pipe 25 will cause the 15 ice-plug to be wholly or partially blown out of the end of said pipe.

The accumulation of higher pressure in the chamber 16 and cap 14, due to obstruction as in the next preceding paragraph described, will obviously act upon the piston 8 to force the same downwardly against the action of the spring 7 and thereby effect an opening movement of the needle valve 10 to an extent to completely withdraw the projection 12 from the intake opening and thus promote more rapid and, in fact, almost instantaneous building up of pressure in the pipe 25 to the point up to the maximum, above stated, necessary to break up or eject 30 the ice-plug before the latter can be built up to a point capable of resisting the maximum pressure.

Immediately following the breaking up or ejection of the ice-plug, release of pressure, in excess of the hydrostatic head of the water, takes place in pipe 25, this being evidenced by a puff of the trapped air and instant return of the piston 8 and the needle valve 10 to normal position. This reciprocatory movement of the valve 10 causes the projection 12 to further cleanse the air-intake opening.

If, for example, conditions should be such that it became advisable to feed a larger 45 volume of air to the pans for a time, or, by reason of accident to the high pressure compressor, a low pressure source of supply should have to be substituted, the member 3 may be very slightly rotated relatively to 50 the housing 1 to unseat the cap 14 and permit the air to by-pass the interior of the latter, thereby partially or completely eliminating automatic operation of the valve 10. The frictional resistance to relative rotation 55 of the housing 1 and member 3 afforded by the spring 29 and cup-washer 31 will serve to maintain the same firmly in any relative positions to which they are turned. This manual operation may also be resorted to at 60 intervals for the purpose of blowing out solids finding their way into the several chambers and passages other than the interior of the cap 14.

For purposes of ready identification, the 65 needle valve 10 may be regarded as the main

or automatic valve of the structure, and the cap 14 as an auxiliary or manually operable valve.

It will also be noted that the device includes the rubber tube 24 connecting the 70 valve casing with the metal tube 25 projecting into the pan and constituting, at its lower end, the discharge point for the air. The rubber tube 24 permits the operator to momentarily shut off the supply to the tube 75 25 and thus to build up pressure in the valve casing for the purpose of fully opening the intake port by reason of response of the piston to the pressure to thereby insure the removal of obstructions from the intake 80 port. To do this it is only necessary to pinch and collapse the tube 24 between its ends and so hold it for a few seconds. This operation also affords a means for ascertaining the condition in the pan so far as 85 the extent to which the water therein is frozen since the resistance to pinching and collapsing of the rubber tube clearly indicates whether the air therein is under the normal low pressure or the maximum pressure. The rubber tube 24, when operated as above pointed out, constitutes the equivalent of a valve normally maintained open by 90 a spring.

The rubber tube 24 may be of such thickness as to expand under the influence of the maximum pressure to a degree to release it from engagement with the tube 25 as the maximum pressure is developed therein only 95 when the ice cake is practically completely formed so that disconnection of the rubber tube from the tube 25 will indicate to the operator that no further supply of air is required. The slush ice first obstructing the lower end of the tube 25 is removed by pressures usually far below the maximums and when the latter fails to effect such removal it is because freezing has progressed substantially to completion.

In some of the smaller plants, where a single operator or watcher can easily make the rounds of all the pans wherein the ice cakes are approaching finished condition, it being at this time that the ice-plugs are most likely to develop in the discharge ends of the tubes 25, and has plenty of spare time to manually remove such plugs, the non-automatic type of valve shown in Figs. 6 to 11 will answer requirements. As this structure includes a main valve and an auxiliary valve, it may be regarded as another embodiment of the invention in so far as the latter is not defined in the appended claims as automatic to the extent above described.

This structure includes the housing element 1 and its stem 2, the valve seat 33 at the inner end of the bore of the latter upon which the upper end of the element 34 seats, the latter constituting a part of auxiliary or manually operable valve element 35. The 120 125 130

latter is integral with the nozzle 36, to which the rubber tube 24 connected with the air discharge or feed-pipe 25 is adapted to be attached, and is externally threaded between its ends to engage the internal threads in the lower part of the housing 1. Its upper end portion 37 is of smaller diameter than the interior of the housing 1 and is externally threaded to receive the said member 10 or element 34 which is internally threaded at its lower end. The extreme upper end portion 38 of said member 35 is externally conical and presents a thin wall of ductile metal bordering the intake end of its central bore 39. The member 34 has a central opening into which the said thin wall projects and which it hugs, so that, upon a downward adjustment of said member 34, the said thin ductile wall will be contracted 20 annularly to partially choke the intake end of said bore 39, thereby effecting a permanent adjustment of the latter to control the volume of air capable of being passed therethrough. This bore is further partially 25 choked by the pin 40 which has its head 41 loosely engaged in a countersunk portion 42 at the intake end of the stem 2, said portion 42 being covered by a screen 43 which is held in place between the upper end of the conical 30 portion of said counter-bore and overturned or crimped edge of the wall of the stem above the latter. The pin 40 is thus free to swing and rotate relatively to the stem 2 to thereby maintain the intake end of the bore 39 35 clear of obstruction.

The bore 39 communicates with the annular chamber 33^a around the member 34 through the openings 44 so that, when said member 34 is unseated, the air will pass 40 mainly from said stem 2 through the chamber 33^a and openings 44 into the unchoked portion of the bore 39.

Between the nozzle 36 and the first mentioned threads of the member 35, the latter 45 is hexagonal and of larger diameter, as shown at 45, there being an annular groove between the ends of said hexagonal portion into which a split wire ring 46 is sprung to form a stop. A cup element 47 having a 50 hexagonal opening 48 in its bottom which receives the upper hexagonal portion 45 and rests upon the stop 46, is disposed to receive the lower cylindrical portion 49, of the housing 1, said portion 49 being, in effect, an annular flange at the lower end of said housing. Within the latter there is mounted a leather washer 50 and a metal washer 51 against which the upper end of the compression spring 52 bears, the latter being 55 substantially the same external diameter as the longer diameter of the hexagonal portion 45 and seating on the upper end of the latter to thereby confine the bottom of the cup 47 between said flange and said spring. 60 Said cup is externally knurled and consti-

tutes a means for digitally rotating the member 35 against the resistance afforded by the spring 52 and washer 50, the purpose of the last-mentioned elements being to hold the members 1 and 35 in any relative position to which they may be adjusted to thus control the volume of compressed air fed to the tube 25.

In use, the member 34 is normally seated to thus compel all air to pass into the bore 75 39 around the pin 40, the said bore having been previously choked by means of the member 34 to the extent demanded by the conditions incident to the particular place of installation. The operator, in making 80 rounds at intervals, can readily rotate each of the cup elements 47 to momentarily unseat the member 34 and thus permit or cause a temporary strong blast of air to be projected from the tube 25 to clear the latter, 85 this operation being necessary only when the cakes of ice are nearing completion and being frequent at this period. This operation also serves to effect a relative longitudinal movement between the pin 40 and the portion of the bore surrounding the same and thus keeps the latter free of obstruction.

If the plant uses only a low-pressure blower to supply the air, the auxiliary valve may be adjusted to a normal position for a 95 steady supply of air and the rim of the cup 47 and the flange 49 marked to indicate this normal position, a further downward adjustment of the member 35 being effected at intervals to increase the volume of the air 100 supply for purposes above set forth.

The member 34 is preferably hexagonal externally at its upper end portion to accommodate a wrench.

All of the several parts of the respective 105 embodiments illustrated and described are designed for production by automatic screw machines supplemented by drill-press and punch-press work so that they may be most economically supplied to the consumer.

It will be observed that both embodiments of the invention shown and described, present the feature of self-cleansing by a vibratory motion of the free end portion of the valve under the influence of air flowing 115 through the structure, the automatic valve possessing the further advantage of a reciprocatory motion resulting from increase in back-pressure due to clogging of the discharge portion of the duct. The direction 120 of travel of the air or other fluid may be reversed in the case of either of the embodiments shown and described without in any way affecting the self-cleaning functions thereof. In case of reversal of flow of fluid 125 through the structure of Figs. 1 to 5 inclusive, the area of the lateral opening 32 in the cap 14 should be so proportioned to the area of the valve controlled opening of the latter as to insure a normally lower pressure 130

within said cap than is presented by the source from which the air or other fluid is received so that, upon clogging of the valve controlled opening (as distinguished from choking), or upon clogging of the passage into which the air or fluid is discharged, the increase in pressure within said cap will be sufficient to actuate the piston against the action of its spring to thereby completely free the discharge port or passage, either by the blowing out due to increased volume and pressure of air or fluid, or to let pass the clogging or obstructing matter which may have collected around the portion of the valve projecting into the discharge port of the cap.

Fig. 12 illustrates an embodiment of the invention wherein the casing 1 is omitted and connection between the stem 53, constituting the intake end of the device, and the interior of the cap 14, (which is, in this case devoid of the lateral opening 32) is effected by means of the small passage 54 in the wall of the cylinder, which connects with the lateral passage 55 connecting with the bore of the stem, the bore or passage 54 being so proportioned to the normal area of the outlet port when partially choked, as to prevent the normal fluid pressure in the cap from reaching a point in excess of, for example, one-half or one-quarter the pressure in the bore of the stem 53. The free space around the free end of the valve being much narrower than the diameter of the passage 54 solids capable of passing through the latter may obviously be accumulated around the discharge port until the latter is clogged to the extent of causing such an increase in pressure within the cap as will actuate the piston to withdraw the valve entirely from the discharge port and thus permit the accumulated matter to be blown out. The spring must necessarily exert a pressure on or resistance to movement of the piston properly proportioned to the relative areas of the passage 54 and exhaust port to permit the piston to respond to the increase in pressure resulting from clogging of the exhaust port.

50 A structure such as is illustrated in Fig. 12 is well adapted for water discharge nozzles for air washing apparatus and possibly also, for certain types of high pressure gas feed nozzles or burners wherein a continuous feed of gas is very essential and automatic cleaning and clearing of discharge port is highly desirable.

While embodiments shown are described only with reference to use in ice-making plants, it will be obvious, of course, that they may be otherwise used in the industries either in the identical forms illustrated or modified to particularly adapt them to other uses, without departing from the invention as defined in the appended claims.

I claim as my invention:

1. An air feed device for ice plants including a valve-casing having intake and discharge ports, a valve therein projecting through and partially choking the intake port for permitting continuous flow of a minimum volume of air under pressure through said casing, a fluid pressure responsive, spring-held element associated with said valve and normally maintaining the same in said position against the pressure of air passing the same and adapted, upon increase of pressure in the casing due to obstruction of the discharge port, to move said valve to fully open the intake port, an air discharge tube, and a manually operable normally open element interposed between said tube and the discharge end of said casing for permitting digital choking of said discharge port for effecting actuation of said valve.

2. An air feed device for ice plants including a valve-casing having intake and discharge ports, a valve therein projecting through and partially choking the intake port for permitting continuous flow of a minimum volume of air under pressure through said casing, a reciprocatory fluid pressure responsive spring-held element carrying said valve and normally maintaining the same in said position against the pressure of air passing the same and adapted, upon increase of pressure in the casing due to obstruction of the discharge port, to move said valve in the direction of travel of the air to fully open the intake port, an air discharge tube, and a manually operable normally open element interposed between said tube and the discharge end of said casing for permitting digital choking of said discharge port for effecting actuation of said valve.

3. A valve casing having an intake and a discharge port, a spring-held piston in said casing carrying a valve member normally positioned to maintain said intake port partially open for the passage through said casing of a minimum volume of fluid under pressure, an air exhaust port associated with the piston to permit free response of the latter to fluid pressure against the action of said spring for effecting quick full opening of said intake port upon clogging of the discharge port by accumulation of fluid pressure within the casing to thereby effect blowing out of the obstruction in the discharge port, said valve member projecting into the intake port for effecting cleansing thereof during reciprocatory movements of said member.

4. A valve casing having an intake and a discharge port, a spring-held piston in said casing carrying a valve member normally positioned to maintain said intake port partially open for the passage through said casing of a minimum volume of fluid under

pressure, an air exhaust port associated with the piston to permit free response of the latter to fluid pressure against the action of said spring for effecting quick full opening of said intake port upon clogging of the discharge port by accumulation of fluid pressure within the casing to thereby effect blowing out of the obstruction in the discharge port, said valve member projecting into the 10 intake port and loosely associated with said piston for permitting limited lateral movement of said valve member in contact with the inner surface of the intake port for maintaining the latter free of obstructions.

15. 5. A valve casing having an intake port at one end and a discharge port at its other end, the latter being always open, a fluid pressure responsive member between the ends of said casing, a valve member carried 20 thereby and normally positioned to partially choke said intake port for permitting a minimum volume of fluid under pressure to pass through said casing, said valve member loosely associated with said fluid pressure 25 responsive member and projecting into said intake port for movement therein when in normal position for maintaining said port free of obstructions.

6. A valve casing having intake and discharge ports at opposite ends, the latter always fully open, a freely rotatable valve member normally partially choking said intake port to permit constant flow of a minimum volume of fluid under pressure through 30 the said casing and maintained normally in motion by inflowing air to maintain said intake port free of obstruction, a spring-held fluid pressure responsive element within the casing carrying said valve-member, a stop 35 for said element against which it is held by said spring, said element adapted to respond to increase in normal pressure of fluid within said casing due to choking of the discharge port to effect rapid full opening of said intake port to permit passage of a larger volume of fluid under pressure to free said discharge port of obstruction and thereupon return 40 said valve member to normal position.

7. A valve casing having intake and discharge ports at opposite ends, the latter always fully open, a valve member normally partially choking said intake port to permit constant flow of a minimum volume of fluid under pressure through the said casing, a 45 spring-held, fluid pressure responsive element within the casing having universal joint connection with said valve member for permitting rotary movement of the latter under the influence of the flow of fluid past the same, said member projecting into the intake port and maintaining the latter free of obstruction by said rotary movement, a stop for said element against which it is held by said spring, said element adapted to respond 55 to increase in normal pressure of fluid within

said casing due to choking of the discharge port to effect rapid full opening of said intake port to permit passage of a larger volume of fluid under pressure to free said discharge port of obstruction and thereupon return 60 said valve member to normal position.

8. An air-supply valve including a casing having an air inlet port bordered at one end by a valve-seat, a valve member having threaded engagement with said casing for adjustment relatively to said seat and having an air discharge port, an air by-pass duct through said valve member communicating with said discharge port for continuous passage of air when said valve is seated, a laterally movable member maintained in motion by the air passing through said intake port projecting into the intake end of said by-pass for partially choking the same and maintaining it clear of obstructions and a 70 spring-held fluid pressure responsive member pivotally associated with said member for withdrawing the same from said intake end as the pressure within said casing increases responsively to choking of the discharge port.

9. An air-supply valve including a casing having an air inlet port bordered at one end by a valve-seat, a valve member having threaded engagement with said casing for adjustment relatively to said seat and having an air discharge port, an air by-pass duct through said valve member communicating with said discharge port for continuous passage of air when said valve is seated, a member maintained in motion by the air passing through said intake port longitudinally and laterally movable relatively to said valve member and projecting into the intake end of said by-pass for at least partially choking the same and maintaining it free of obstruction, a chamber in said casing open at one end to atmosphere, and a spring-held valve therein arranged to prevent leakage from 80 said casing and operatively associated with said member to withdraw the same from said intake end as said valve moves responsively to increase in pressure within the casing due to choking of the discharge port.

10. A valve for feeding a normal predetermined volume of fluid under pressure against back-pressure which includes a casing having a passage therethrough, a member adjustably mounted in said casing and having a passage therethrough constituting a continuation of the passage through said casing, a valve-seat at the discharge end of the latter, said member including a valve element seating on said valve-seat, a spring-held valve carried by said member and normally partially choking the passage in the latter, to thereby limit the passage of fluid through the said member when said valve element is seated, the latter adapted to be unseated to thereby effect by-passage of the 115

fluid with respect to said spring-held valve.

11. A valve for feeding a normal predetermined volume of fluid under pressure against a predetermined back-pressure which includes a casing having a passage therethrough, a member adjustably mounted in said casing and having a passage therethrough constituting a continuation of the passage through said casing, a valve-seat at the discharge end of the latter, said member including a valve element seating on said valve-seat, a spring-held valve carried by said member and normally choking the passage in the latter, at least in part, to thereby limit the passage of fluid through the said member when said valve element is seated, the latter adapted to be unseated to thereby effect by-passage of the fluid with respect to said spring-held valve, said spring-held valve loosely associated with said member to permit free lateral movement thereof with respect to the portion of the passage choked thereby to effect automatic cleansing of said portion of said passage.
12. A discharge nozzle for fluid under pressure including a casing having a passage therethrough, there being a back-pressure chamber between the ends of said passage, a cylinder communicating at one end with atmosphere and at its other end with said chamber, a spring-held piston in said cylinder, a valve element carried thereby normally positioned to partially choke said passage, the spring for said piston cooperating with the inlet of air into said chamber and the normal back-pressure afforded by the discharge end of said passage to maintain said valve element in predetermined position so long as the discharge end of said passage is free from other obstructive matter and continues to discharge the normal volume of fluid, and automatically effecting a reciprocatory movement of said piston and valve element upon increase of back-pressure due to clogging of said discharge end of said passage in whole or in part, to thereby effect ejection of the obstructive matter, said valve element having universal joint connection with said piston and adapted to be maintained in motion by the fluid passing the same to thereby maintain clean the said choked portion of said passage.

13. A fluid supply valve including a casing having an air intake port bordered at one end by a valve-seat, a valve adjustable relatively to said seat, a main discharge port for air passing said valve, a by-pass duct communicating with said discharge port and

having its intake end disposed to communicate with said intake port when said valve is seated, a valve controlling said by-pass duct for effecting normal delivery of a very minute volume of fluid from said discharge port, and fluid pressure actuated, spring-held means associated with said by-pass valve for automatically effecting full opening of said by-pass duct in event of clogging of the discharge port for clearing the latter of obstructions.

14. An air supply valve including a casting comprising two parts rotatable relatively to each other, an air intake port in one of said parts, an air discharge port for the other of said parts, a valve carried by the latter for controlling said intake port and adapted to be moved toward and from the latter as said parts of said casting are relatively rotated, an auxiliary intake port in said valve communicating with the intake port of the casting when said valve is seated, a spring-held fluid pressure responsive valve controlling said auxiliary intake port for permitting constant flow of a minimum volume of air through said casting when said first named valve is seated and adapted to automatically effect full opening of said auxiliary port upon increase of normal pressure in said casting due to clogging of the discharge port.

15. A device for maintaining a constant controlled flow of fluid under pressure against a substantially constant hydrostatic resistant which comprises a casing having an intake port for association with a source of fluid under pressure, a discharge port from said casing, a passage therein between the intake and discharge ports communicating at one end with atmosphere, a spring-held reciprocable fluid pressure responsive valve in said casing shutting off the connection between the latter and atmosphere, a freely rotatable choke member pivotally associated with said valve and normally projecting into said discharge port, said member being maintained in motion by incoming fluid to maintain said intake port free of obstruction and being withdrawn from said port by said valve as the latter is moved responsively to increase in pressure in said casing due to increase of the normal resistant to discharge from said casing, and a member in the latter manually adjustable to effect by-passage of fluid relatively to said intake port to increase the rate of discharge from said casing.

IRVING COWLES.
